UNITED STATES PATENT OFFICE.

LOUIS F. KOEHLER, OF CHICAGO, ILLINOIS.

DENTAL ANVIL OR SWAGE-BLOCK.

1,111,392.

Specification of Letters Patent. Patented Sept. 22, 1914.

Application filed December 22, 1913. Serial No. 808,089.

To all whom it may concern:

Be it known that I, LOUIS F. KOEHLER, a citizen of the United States, and a resident of Chicago, in the county of Cook and State of Illinois, have invented certain new and useful Improvements in Dental Anvils or Swage-Blocks; and I do hereby declare that the following is a full, clear, and exact description thereof, reference being had to the accompanying drawings, and to the characters of reference marked thereon, which form a part of this specification.

This invention relates to improvements in dental anvils or swage blocks, and the invention consists in the combination and arrangement of the parts hereinafter set forth and more particularly pointed out in the appended claims.

Among the objects of the invention is to provide a swage block or anvil composed of a relatively soft anvil body and a rigid sustaining frame, of a construction to permit the anvil body to be quickly and readily removed from and applied to the frame for the purpose of renewal.

A further object of the invention is to provide, in combination with such an anvil, means to support the frame to permit the anvil body to be readily driven from the frame.

As shown in the drawings:—Figure 1 is a plan view of a dental anvil or swage block embodying my invention. Fig. 2 is a transverse section thereof, showing it inverted over a supporting ring on which it is sustained when the anvil body is to be removed from the frame. Fig. 3 is a side elevation of one form of anvil body. Figs. 4, 5 and 6 are transverse sections of other forms or modifications, the latter showing a modified form of supporting ring for the anvil frame. Fig. 7 is a transverse section, partially broken away, of a further modification.

An anvil or swage block embodying my invention comprises a frame having a through opening constituting a chamber or recess to receive a soft metal anvil body and provided at one side with a surface or shoulder over which a portion of the anvil body is up-set to constitute a locking engagement between the frame and the anvil body of such nature, however, as to permit the anvil body to be driven or forced from the frame for the purpose of renewing the anvil body.

As shown in Figs. 1 to 6, inclusive, of the drawings, 10 designates a cast metal frame

which is formed at its upper side with a raised marginal flange 11 to provide within the flange a depression or recess to receive a body 12 of relatively soft material, such as lead, Babbitt or the like, the outer face 14 of which constitutes the anvil face of the block. The said flanges 11 laterally support the relatively soft anvil body 12 so as to prevent lateral displacement of the same under hammer blows. As shown in Figs. 2, 4, 5 and 6, the frame 10 is provided centrally with an opening 15, and the anvil body 12 is provided with an internal lug 16 which is adapted to extend into said opening 15, with its outer or free end substantially flush with the lower side face of the body 10. As shown in Figs. 3, 5 and 6, the lower end of the opening 15 is beveled or countersunk at 17 to form a tapered shoulder against which the end of the lug is upset to constitute interlocking connection between said parts.

In Fig. 4 the shoulder or surface against which the anvil body or an extension thereof is upset has the form of a long taper extending from end to end of the opening 15. In Fig. 5, the central opening 15 is formed with straight walls, and the interlocking shoulder or surface on the frame and anvil body are formed at the bottom side of the frame.

When the anvil body is to be renewed, the said body may be removed from the frame by pressure or blows applied to the extension or lug 16 through the medium of a suitable punch. In order that the anvil body may readily free itself from the frame the wall of the opening 15 and the inner sides of the flange 11 may be tapered with an upwardly flaring effect.

To facilitate the removal of the anvil body, the said frame may be provided with a flange 20 which is adapted to rest on the upper end of a hollow support 21, into which the flange 11 extends, so as to support the anvil frame a distance above the surface on which the frame 21 rests, and to thereby enable the anvil body to clear itself of the anvil frame when said body is forced away therefrom.

In lieu of the arrangement shown in Fig. 2, I may provide the support 23 (Fig. 6) with an interior annular shoulder 24 upon which the frame flange 11 is directly supported when the frame is mounted and in position to force the anvil body therefrom.

In Fig. 7 the anvil frame 27 has the form of a short section of a tube or ring, and is provided at one end with a shoulder or surface 28 outwardly against the adjacent end of the anvil body 29 is up-set to form an interlocking connection between the anvil body and the frame. In this construction, by reason of carrying the full diameter of the anvil body from one side to the other of the ring like frame, both faces of the anvil body may be utilized. When the anvil body is to be replaced, the said ring like frame may be placed upon a supporting frame, such as is shown in Fig. 6, and the body driven downwardly or outwardly away from the frame. In said latter construction, the inner side of the ring like frame may be roughened, as shown at 30, so as to prevent shifting of the anvil body relatively to the frame in the ordinary use of the device.

The construction shown permits the anvil body, of whichever type illustrated, to be cast in suitable forms and to be sold as renewing parts of the anvil or swage block. The construction also permits the separately formed anvil body to be readily locked to the frame and also readily removed therefrom when the same is to be renewed.

I claim as my invention:—

1. An anvil or swage block comprising a frame having a through opening, a removable and renewable anvil body therein of relatively soft material supported by the walls of the frame, and means for providing an interlocking connection between the frame and body, constructed to permit said

body to be driven out of the frame, said frame being provided at one side of its opening with an annular surface or shoulder outwardly over which an adjacent annular part of the anvil body is up-set to interlock the body to said frame.

2. An anvil or swage block comprising a frame formed at one side with a recess, a renewable anvil body of relatively soft material in said recess, said frame being provided with a central opening having at one end an annular shoulder and the body being provided with a lug or extension which extends into said opening and is upset at its end over said shoulder.

3. An anvil or swage block comprising a frame formed at one side with a recess to receive an anvil body, and provided also with a central opening which extends to the side of the frame remote from said recess, and a renewable anvil body of relatively soft material occupying said recess and provided with a lug which enters said opening, the wall of the opening being formed with an annular flaring surface outwardly over which the end of said lug is adapted to be upset.

In testimony that I claim the foregoing as my invention I affix my signature in the presence of two witnesses, this 6th day of December, A. D. 1913.

LOUIS F. KOEHLER.
